UNITED STATES PATENT OFFICE.

THOMAS TAYLOR, JR., OF HUBBARD WOODS, ILLINOIS.

DESIGN FOR A HEAD FOR GOLF-CLUBS.

44,457.

Specification for Design.

Patented Aug. 5, 1913.

Application filed May 29, 1913. Serial No. 770,761. Term of patent 14 years.

To all whom it may concern:

Be it known that I, THOMAS TAYLOR, Jr., a citizen of the United States, residing at Hubbard Woods, in the county of Cook and State of Illinois, have invented a new, original, and ornamental Design for Heads for Golf-Clubs, of which the following is a specification, reference being had to the accompanying drawing, forming a part thereof.

Figure 1 is a front perspective view of a

golf club, showing my new design; Fig. 2 is a rear perspective view thereof, and Fig. 3 is a bottom face view of the club.

I claim:

The ornamental design for a head for a golf club, as shown.

THOMAS TAYLOR, JR.

Witnesses:

CHAS. C. TILLMAN,
A. S. PHILLIPS.
